UNITED STATES PATENT OFFICE.

CORNELL FLAGSTAD AND OSCAR A. FLAGSTAD, OF MINNEAPOLIS, MINNESOTA.

COLLAPSIBLE CRATE.

Application filed July 25, 1924. Serial No. 728,143.

This invention relates to collapsible crates, and the main object is to provide an improved, efficient and practical crate construction adapted to be used for shipping poultry, machinery, furniture, and commodities of practically every description, and which, when emptied of its contents may be conveniently and compactly collapsed for return shipment to the original shipper, and thus 10 effect a great savings in crating material by enabling the shipper to use the same crate a large number of times, and, by reason of certain features which enables the crate to be compactly collapsed or knocked down, to 15 minimize the space required in a freight car or other vehicle in order to return the empty crate. A further object is to provide novel means for arranging, connecting and detachably securing various crate sections 20 together as and when the crate is being set up ready for use. These and a number of other objects, which will be fully described in the course of the following specification, are affected by the structure which is shown, 25 in preferred and modified forms, in the accompanying drawings, in which:

Fig. 1 is a perspective view of a crate embodying our invention.

Fig. 2 is an enlarged plan view of the 30 detachable cover, as removed from the crate.

Fig. 3 is a detail section on the line 3—3 in Fig. 2, and showing an adjacent end section portion.

Fig. 4 is an enlarged detail section as on 35 the line 4—4 in Fig. 2.

Fig. 5 is an enlarged sectional view, about as on the line 5—5 in Fig. 1.

Fig. 6 is an end view of the crate showing 40 various modifications over the crate shown in Fig. 1.

Fig. 7 is an enlarged sectional elevation in part as on the line 7—7 in Fig. 6, illustrating the method of attaching the end section.

Fig. 8 is an enlarged section as on the line 45 8—8 in Fig. 6.

Fig. 9 is an enlarged fractional detail of an end section corner.

Fig. 10 is an enlarged sectional view, as 50 on a line 10—10 in Fig. 6, showing a modified locking member.

Fig. 11 is an end view of a crate showing further modifications.

Fig. 12 is an end view of the crate shown

in Fig. 11, as locked in its collapsed condition.

Fig. 13 is an enlarged detail section as seen on the line 13—13 in Fig. 11.

Referring to the drawings more particularly and by reference characters, A and B designate the side sections of a crate, which 60 is completed by end sections C and D, a base or bottom section E, and a top or cover section F.

Each of the side sections A, B, consists 65 of outer slats 15, 16 and 17, secured together by a frame consisting of horizontal rails 18 and 19, and vertical end rails 20 and 21. The detachable end sections C, D each consist of horizontal slats 22 and 23, connected by vertical slats 24 and 25, and suitably 70 trussed by braces 26. The ends of the slats 22 are provided with angularly formed male locking irons 27, which are detachably locked or inserted in female locking irons 28 75 on the side sections, by a tilting or swinging movement of the end section (as shown in Fig. 7), so that the devices 27—28 cannot be unlocked when the respective end sections are in a vertical or set up position. The 80 members 28 are preferably formed of heavy strap or sheet metal, and extend over the corner edge and to the under slat 18 so as to greatly strengthen the side section.

At the upper corners of the crate it will 85 be noted that the slats 17 project slightly beyond the slats 20, as at 29; while the ends of the slats 23 (of the end section) abut against and extend beyond the end rails 20 (of the side section) to engage, for bracing 90 purposes, under the projecting end 29 of the slats 17. The ends of the rails 23 are also provided with angle iron members 30, which,

as the upper ends of the end sections are 95 swung into place, engage against the outer edges of the rails 20 and thus securely brace and prevent any spreading tendency of the side sections, when the crate is set up. The locking members 27—28, of course, have the same object at the lower corners of the crate, so that the adjacent ends of the side and end sections will be securely, yet detachably, secured together in a very rigid manner.

The upper ends of the end sections are 100 locked in place by angle irons or depending hooks 31 of the cover section, which will 105 now be described.

The cover F consists of a main body portion or member 32, having cleats 33 at its ends, which are spanned by three slats 34, 35 and 36 so as to form a limited space between the slats and the member 32. A pair of levers 38 and 39 are secured for swinging movement in said space, and are respectively pivoted as at 40 and 41 to the slats 34 and 36. A locking member 42, having a finger groove 43, is secured by spring hinges 44 to the slat 35, in such a manner that it will normally engage between the longer ends of the levers 38, 39, and hold them apart, but when lifted up will permit the levers to be swung in, as indicated by the dotted lines 45 in Fig. 2. When in the dotted line position 45 the ends of the levers will not project beyond the outer limits of the cover, which can then be moved down into place between the members 19 of the side sections. The ends of the cover extend far enough out so that they will rest on the end sections C, D, and so that the hooks 31 will properly engage the slats 23. Now, when the levers 38, 39 are to be moved into parallel or transverse positions so that their ends will lock under the side section members 19 they will be moved through the position, for instance, as indicated by the dotted lines 46 (for lever 39). This, in view of the fact that the levers have comparatively short and long ends from their fulcrums, causes the short ends to project beyond the cover for locking engagement before the long ends do. This is a very valuable feature in some classes of crates, for instance where the contents or packing material in the crate must be pressed down by the cover, as it permits one corner of the cover to be pressed down and locked in place at a time, until all four levers or lever ends are swung into place, where they are then held in place by the member 42. The levers may even be swung beyond this point, but will not go far enough to be released from their locking position.

The bottom section E of the crate shown in Fig. 1 is detachable, and consists of transversely crossed slats 47 and 48, the ends of the latter of which are supported on the bottom pieces 18 of the side sections. The crate may be used, under certain circumstances, without the bottom E, in which event the machine, piece of furniture or other article would have to be supported either on the members 18 or in some other suitable manner, as, for instance, by temporary cross braces secured to the side or end sections. In either event the crate could be relieved of its contents and collapsed in a very simple manner and in but a few minutes time, and without lifting such contents bodily out of the crate. Thus, the cover would first be detached, then the end sections might be pulled or moved away,

after which the side sections could be readily removed. If a bottom has been used the machine or other article may be jacked up so that the bottom section may be pulled out, and placed, together with the cover 70 and end sections, in the side sections, which are then secured together, for return shipment, as will later be described.

In the crate shown in Figs. 6, 7, 8 and 9, the various crate sections A¹, B¹, C¹, E¹, and F¹, are substantially the same as the corresponding sections shown in the crate of Fig. 1, except for the following modifications.

Each end section (C¹) is provided with 80 the above described securing member 27 at its lower corners, for engagement with the side section straps 28, but at its upper corners each end of the slat 49 is provided with a channel 50 and a bridging pin or 85 member 51. The adjacent upright 52 of the side section A¹ (or B¹) is provided with a latch member 53 which is received in the channel 50, and which has a spring closed finger operated bolt 54, which detachably 90 locks the pin 51 in a slot in the latch member, so that the upper end of the end section will be securely locked in place or set up position whether or not the hooks 31 of the top section are employed. The 95 primary object of the latch 51—53, however, is to hold the end sections in place while the crate is being filled or packed, when the cover F¹ is off, which, it may be noted, would not be affected by the structure 100 shown in Fig. 1.

A further improvement or advantage of the crate shown in Fig. 6 is the method by which the removable bottom E¹ is secured in place by the end sections. Thus the base 105 section is provided with strips 55, which are engaged and pressed firmly downwardly by suitable members 56 secured on the lower ends of the end sections. Thus, the bottom will be rigidly secured in the crate, and if 110 a heavy article, such as a stove, indicated by 57, is bolted, as at 58, to the bottom, it also will be rigidly secured in the crate, and in that event it may even be possible to dispense with the cover section entirely.

In the modification shown in Fig. 10, a single iron 59, having an integral offset portion 60 is received by the slot 61 of the end section member 49. Such iron would obviously tend to brace the sections rigidly together, when set up, but would require that other means (such as 30, 31, or 51, 53, or 62—65) be also used to prevent the side and end sections from falling away from each other.

Turning now to the crate shown in Figs. 11, 12 and 13, the various crate sections will be referred to as A², B², C², E², and F². The object of this construction is to illustrate novel devices for securing the side and end 130

sections together, when the crate is set up (as in Fig. 11), and which will also lock the side sections together when the crate is collapsed, as illustrated in Fig. 12. Thus 5 the section B³ is provided (near each end) with a pair of hooks 62, which engage loops 63, at one side of the adjacent end section C³, and the opposite side of the end section is provided with hooks 64 which are arranged to engage loops 65 of the side section A³. So that a downward movement of the end section will secure it to both side sections. The hooks and loops are so arranged with respect to each other, that when the 10 crate is collapsed (as in Fig. 12) and the top bottom and end sections are contained within the side sections, the latter two may be moved into locking engagement by the hooks 62 and loops 65.

20 A lock, which may also of course be used on any of the other crates shown, is provided in the form of a latch member 66, which may be identical in construction with the 25 latch 53, having a finger bolt 67 and a receiving slot 68. A bail 69 is pivotally secured, as at 70, to the side section A³, and is arranged to drop in the slot 68, when the side sections are together, so as to securely lock them together until the crate is to be 30 again set up.

It is understood that various and suitable modifications may be made in the general design and structural details of the crate

construction herein set forth, provided, however, that such modifications come within 35 the spirit and scope of the appended claims.

Having now therefore fully shown and described our invention, what we claim to be new and desire to protect by Letters Patent is:

1. The combination with a crate having a detachable cover for closing the same, of a pair of levers pivotally secured near diagonally opposed corners of the cover, said levers having short arms for initial engagement with the crate and relatively long arms for secondary engagement with the crate, means for limiting the outward swinging movement of the long arms and a locking member for releasably limiting the inward 50 movement of the long arms.

2. The combination with a crate having a detachable cover for closing the same, of a pair of levers pivotally secured near diagonally opposed corners of the cover, said levers having short arms for initial engagement with the crate and relatively long arms for secondary engagement with the crate, and a movable spring actuated member arranged to engage the levers and secure them 55 in locked position with respect to the crate.

In testimony whereof we affix our signatures.

CORNELL FLAGSTAD.
